UNITED STATES PATENT OFFICE.

GEORGE SHAMBECK, OF SALT LAKE CITY, UTAH, ASSIGNOR OF ONE-HALF
TO GEORGE ROTH, OF SALT LAKE CITY, UTAH.

POLISHING COMPOUND.

SPECIFICATION forming part of Letters Patent No. 747,003, dated December 15, 1903.

Application filed June 10, 1903. Serial No. 160,861. (No specimens.)

To all whom it may concern:

Be it known that I, GEORGE SHAMBECK, a subject of the German Emperor, and a resident of Salt Lake City, in the county of Salt Lake and State of Utah, have invented new and useful Improvements in Polishing Compounds, of which the following is a full, clear, and exact description.

This invention relates to a certain novel and useful polishing compound, and has particular application to a polish designed especially for use on articles of furniture, vehicles, and woodwork in general.

In carrying out the present invention I have particularly in view forming a polish of a compound or admixture of easily-obtained ingredients and which will embody the essential features of cheapness and facility in preparation.

A further object of my invention is to provide a polish which may be employed for any article of furniture, whether such article has been previously varnished or not, said polish imparting to the article to which it is applied a bright and fresh appearance, so that the article thus treated will look as though it had recently been renovated or was an entirely new article fresh from the hands of the manufacturer.

The compound forming the subject-matter of this application is also of such nature that it is perfectly waterproof—that is to say, when applied to a buggy, railway-car, or the like water will be readily shed from such article

instead of impregnating or soaking the same, thus preventing the possibility of warping the structure under the effects of heat or the sun.

With the above objects and others of a similar nature in view my improved polish consists of a compound formed of the ingredients hereinafter set forth.

In making my improved compound I mix turpentine, raw linseed-oil, grain-alcohol, and muriatic acid, and while the proportions of the same may be varied still I have found it preferable to employ the ingredients in the following proportions: spirits of turpentine, two and one-half ounces; raw linseed-oil, one and three-fourths ounces; grain-alcohol, three ounces, and muriatic acid two and one-half ounces, the acid being diluted with approximately two and one-half ounces of water.

The compound acts the same either on a wet or dry surface, and when it is desired to brighten any articles the polish may be applied with a cloth or the like, a larger or smaller amount of the polish being applied, according to the condition of the article to be treated.

Having thus described my invention, I claim as new and desire to secure by Letters Patent—

1. The herein-described polish composed of spirits of turpentine, raw linseed-oil, grain-alcohol and muriatic acid.

2. The herein-described polish composed of spirits of turpentine, raw linseed-oil, grain-alcohol, and diluted muriatic acid.

In testimony whereof I have signed my name to this specification in the presence of two subscribing witnesses.

GEORGE SHAMBECK.

Witnesses:

WALTER K. PERKINS,
IDA F. PARSONS.
